ATTORNEY.

UNITED STATES PATENT OFFICE

FRED DOWNEY, OF FORT WORTH, TEXAS, ASSIGNOR OF ONE-HALF TO M. H. MARR,
OF FORT WORTH, TEXAS

PUMP

Application filed February 7, 1930. Serial No. 426,515.

My invention relates to pumps and more particularly pumps for various liquids, such as oil, water, and other liquids; and the object is to provide pumps which are adapted to pump liquids from deep or shallow wells; to provide certain devices for preventing displacement of important parts of the pumping apparatus; to provide parts which are replaceable; to provide devices which will automatically replace or restore parts to their normal positions after operations; to provide pumps by which a constant discharge of liquids will be pumped during the time of operation without employing air chambers or any other sort of compressing means, and to provide pumps which are highly efficient in operation and give satisfactory results in pumping various kinds of liquid from wells. Other objects and advantages will be fully explained in the following description and the invention will be more particularly pointed out in the claims.

Reference is had to the accompanying drawings which form a part of this application.

Figs. 1, 2, and 3 are vertical sections, one being a continuation of the other in succession, of the entire pump.

Fig. 4 is a plan view of the upper intake valve assembly, taken on the line 4—4 of Fig. 1.

Fig. 5 is a vertical section of the same, taken on the line 5—5 of Fig. 4.

Fig. 6 is a plan view of the lower discharge valve assembly, looking downwardly from the line 6—6 of Fig. 3.

Fig. 7 is a plan view of the lower intake valve assembly.

Figs. 8 and 9 are detail views of the T-tool connection.

Similar characters of reference are used to indicate the same parts throughout the several views.

The drawings show the pumping apparatus located in a well casing 1. The discharge chamber 2 serves not only as a discharge chamber, but serves to contain the springs 3, (four in number) in place and these springs are secured to the chamber 2 by rivets 4. The springs 3 serve to hold the standing valve as-

sembly downwardly during normal operations, and prevents displacements of the valve assembly upwardly. The springs 3 are sufficiently yielding to permit the withdrawal or insertion of the working parts and traveling valve or piston, while the pump remains in the well. The upper polish rod 5 is connected to the sucker rod 6 by a coupling 7. A spring retainer 8 is loosely mounted on the upper polish rod 5 so that the polish rod 5 will move freely therethrough. A spring 9 serves to force the valve 10 back in its seat 11. A packing gland 12 is formed integral with the valve 10. Packing 13 is mounted in the gland 12 and a metallic washer 14 is mounted on top of the packing 13. The lower end of the packing gland is beveled in the interior part. The washer 14 cooperates with the beveled portion 15 to cause the packing to bear on the polish rod 5. A spring 16 is mounted on the washer 14 and a hollow plug 17 is screwed in the gland 12 compressing the spring 16. The spring 16 serves to keep tension on the packing 13. The polish rod 5 moves through the valve 10 and the packing 13 which prevents any leaking around the polish rod 5.

The upper valve assembly includes a head 18 which is connected to the discharge chamber 2 by a coupling 19. The valve seat 11 is screwed into head 18. The head 18 has a plurality of openings 20 therethrough for the passage of liquid. The head 18 has intake ports 21 and the intake is controlled by spring pressed balls 22 and seats 23 and the ball valves 22 are opened only on the downstroke of the pump and closed on the upstroke of the pump. The ports 21 communicate with the interior of the head 18 by means of passages 24 which lead upwardly through the seats 23. The interior of the head 18 is sealed from the discharge chamber 2, a metal washer 25 and a gasket 26 co-operating therewith. The valves 22 move vertically in cylindrical openings 27, which communicate with ports 28 which lead into the inner chamber of head 18. The valves 22 are opened on the downstroke and these valves are closed instantly on the upstroke by springs 30. A stop 31 for the spring 9 is placed inside of the

100

spring and rests on the plug 17 ordinarily and serves to prevent crushing the spring on insertion or removal of traveling valve or piston.

5 A lower discharge chamber 32 is connected to the head 18 by a coupling 33 and serves as a conveyance for liquid upon and around the working barrel 29. The chamber 32 is connected to the lower discharge valve assembly which includes a head 34 by a coupling 35. 10 The working barrel 29 is screwed into the upper end of head 34. The head 34 has a plurality of cylindrical vertical openings 37 therethrough for the movement of the ball valves 36. Seats 38 are inserted through openings 37 from the top of the head and rest on shoulders 39 formed in the head 34. The openings 37 are reduced at the lower ends to the interior diameters of the seats 38, thus forming 15 the shoulders 39. At points shortly above the seats 38, the openings are cut together by slots 40 to provide for passage of fluid past the ball valves 36, the slots 40 being too narrow to permit displacement of the balls through the slots. A perforated plate 41 is secured on the head 34 and has openings corresponding to the openings 37 through the head but the openings in the plate 41 are staggered relative to the openings 37 so that the balls will not 20 pass through the plate. The head 34 is connected to the lower standing valve assembly head 42 by screwing the head 42 into the lower end of the head 34 to avoid enlarging the outside diameter of the pump. The head 42 has a plurality of vertical cylindrical openings 43, similar to openings 37, but smaller occasioned by the smaller diameter of the head 42. The openings 43 are slotted together by slots 44, similar to slots 40. Ball valves 45 25 move vertically in the openings 43 and are urged downwardly by springs 46. The balls 36 in head 34 are urged downwardly by springs 46 in a similar manner. The balls 45 are provided with inserted seats 47 which 30 rest on shoulders 48 in the head 42. The seats 39 and the seats 47 have interior grooves 49 for convenience in lifting the seats by means of a suitable tool in pulling or insertion of the seats. A plate 41 is secured to the head 42, and has similar perforations and slots to those 35 of plate 41 in head 34. The head 42 is provided with a packing gland assembly 50 similar to the packing gland 12 in Fig. 1, excepting the inverted position.

40 The head 42 is cored out from the bottom and the packing inserted and held in position by an annular washer 51, spring 52 and plug 53.

45 A spring housing 54 is connected to the lower end of head 42 by a coupling 55. A perforated sleeve 56 surrounds the lower end of plug 53 and rests on a seat 57 which seat 57 serves also as a seat for the spring 58. The 50 perforations in sleeve 56 form ports for the passage of fluid. The sleeve 56 prevents the

55 spring 58 from obstructing the passage of fluid through the cylindrical openings 43 in head 42. The spring 58 is in sections divided by special washers 59 which have seats on both sides for the adjacent parts of the 60 spring. The spring 58 is secured to the lower 65 polish rod 60 by a washer 61 and lock nuts 62.

70 The polish rod 5 is connected to the piston core rod 63 by means of a coupling 64. The piston cups 65 are held on the core 63 by nuts 66. The core 63 is connected to a T-tool 75 plug 67 by screwing the plug 67 on the core 63. The plug 67 is screwed into a cup 68. The plug 67 has a groove 69 to receive the spear end 70. The wings 71 of the T-tool 80 spear 70 rest in the groove 72 in the bottom of the cup 68. A slot 73 at right angles to groove 72 is made in the bottom of cup 68 to permit the spear to enter the cup chamber 74. On the entrance of the spear 70 into 85 the cup chamber 74, the spear 70 will be at right angles to the groove 69 and the groove 72. The cup 69 is rotated one-quarter turn so that the spear 70 will register with the groove 69 and be held in position so that the 90 wings 71 will enter groove 72 when tension is taken on the pump rods. When this quarter turn is made, the cup 68 will automatically drop with the spear point entering the groove 69 whereby the wings 71 are held in position 95 to enter the groove 72 when the pump is started. The wings 71 are held in groove 72 due to the constant tension of the spring 58. The T-tool spear shank 75 is screwed onto the lower polish rod 60. This T-tool connection 100 can be made from the surface, however deep the well may be. It will be understood that the pump assembly is below the level of the fluid.

105 On the downstroke of the pump, the weight of the rods is not sufficient to overcome the weight of the fluid in the tubing. Therefore, spring 58 is designed with sufficient strength to pull the rods down and accelerate the movement of the fluid or liquid upward 110 in the tubing, being assisted by the weight of the rods. The spring 58 is also to keep tension on the entire string of rods during the operation of the pump on both up and down strokes thereby preventing any slap or 115 vibration of rods against the walls of the tubing. The spring 58 will also prevent any unscrewing of the rods while the pump is in operation. The spring 58 may be used in both double and single acting pumps, serving 120 similar purposes.

125 In the idle condition, the piston is at the bottom of the downstroke. In commencing an upstroke, the sucker rod and the polish rods are operated from the surface. Fluid will be taken up through the pipe 54, through the seat 57, through ports 56, through the cylindrical ducts 43 in head 42, through valve seats 47 around balls 45, through perforations in plate 41, through head 34, up the 130

working barrel following the piston assembly 65 and the T-tool assembly which is connected to the piston assembly 65, on up the working barrel 29 to the end of the upstroke of pump. On the down stroke, the fluid which has been elevated, or drawn upwardly inside of working barrel 29, is forced downwardly through the working barrel 29 into and through head 34 by means of the piston. The fluid is forced upwardly through valve seats 38 and up through the cylindrical openings 37 around balls 36 and through openings in plate 41 into the chamber of housing 32, upward through housing 32, through head 18 by way of cylindrical openings 20, through openings in washer 26 and plate 25 which register with openings 20, and thence into chamber 2 which swedges into the well tubing. At the same time, fluid is taken through the ports 21 and on up through the cylindrical openings 24 and 27, passing through the seats 23, lifting the valves 22 upwardly, thence through slots or ports 28 by means of the vacuum created by the piston 65 in the working barrel 29 which is sealed off at this time by valve 10, following the piston 65 downwardly through barrel 29 to the end of the down stroke of the piston. The barrel 29 is now filled with fluid above the piston 65 to the level of the ports 28. On the upstroke, this same fluid is forced by means of piston 65 through the barrel 29 and past valve 10 which is lifted by the pressure of the fluid and out into chamber 2 and the tubing.

These operations go on in sequence in the same manner. The pull on the sand in the formations or strata is constant, thereby eliminating all agitation of the sand in the bottom of the well, due to the constant loading and constant discharge of the pump which is the same on the downstroke and upstroke of the piston. The interval at the end of the strokes is so short, that the agitation of the sand will not be commenced. Due to the construction and arrangement of the several parts, the production or out-put of liquids is greatly increased as compared with other pumps of like size. The necessity of counterbalances on the rig at the surface is eliminated and vibration on the rig is eliminated due to the constant tension on the rods affected by the spring at the bottom of the well.

Various changes in the sizes, proportions, construction and arrangement of the several parts may be made without departing from my invention.

What I claim is,—

1. A pump having a discharge pipe, a valve assembly associated therewith, a sucker rod operating through said valve assembly, and radially flexible springs attached to the interior of said discharge pipe and adapted to prevent upward displacement of said valve assembly.

2. A pump having a discharge pipe, a valve assembly associated therewith, a sucker rod operating through said valve assembly, and radially flexible springs attached to the interior of said discharge pipe and adapted during normal operations to prevent upward displacement of said valve assembly but sufficiently yielding to permit insertion of said valve assembly and all working parts of the pump.

3. A pump having a discharge pipe, a valve assembly associated therewith, a sucker rod operating through said valve assembly, a polish rod connected to said sucker-rod, said valve assembly consisting of a head having a central liquid discharge chamber, a plurality of receiving passages in the lower part thereof and intake ports leading to said receiving passages, and a plurality of discharge passages communicating with said receiving passages, valves for opening and closing said receiving passages and a valve movably mounted on said polish rod for said central discharge chamber, means for holding said valves yieldingly in their seats, and radially flexible yielding means attached to the interior of said discharge pipe and engaging said sucker rod for preventing upward displacement of the working parts of the pump during normal operations, but sufficiently yielding to permit insertion and removal of working parts.

4. A pump having a discharge pipe, a valve assembly connected thereto, a sucker rod and yielding means preventing upward displacement of the pump working parts during normal operations, a polish rod and a coupling connecting said polish rod to said sucker rod and bearing against said yielding means said valve assembly having a central discharge chamber therethrough and a plurality of intake ports in the lower part thereof and valve seats therefor, and having a plurality of discharge passages concentrically arranged relative to said intake ports, valves for said intake ports adapted to engage seats, a valve for said central discharge chamber movably mounted on said polish rod, a valve retainer bearing against said coupling, and a spring bearing against said retainer and against said valve.

5. A pump having a discharge pipe, a valve assembly as set forth in claim 4, a working barrel connected to said valve assembly, and a co-operating valve assembly connected to said working barrel and provided with intake and discharge ports.

6. A pump having a discharge pipe, a valve assembly as set forth in claim 4, a working barrel connected to said assembly, a co-operating valve assembly connected to said working barrel and provided with intake and discharge ports, and a piston carried by said polish rod and operating through the latter valve assembly.

7. A pump having a discharge pipe, a valve assembly connected thereto, a working barrel connected to said valve assembly, a sucker rod operating in said discharge pipe, a polish rod connected to said sucker rod and operating in the discharge pipe and through said valve assembly, a working barrel and discharge chamber connected to said valve assembly, a co-operating valve assembly connected to said working barrel and discharge chamber, a lower standing valve assembly connected to said co-operating valve assembly, a piston carried by said polish rod and operating through said co-operating valve assembly, a lower polish rod, a T-tool plug connecting said lower polish rod to said piston, and a spring mounted on said lower polish rod for maintaining tension in said sucker rod and polish rods for cooperating with the weights of said rods in operation.

8. A pump having a discharge pipe, a valve assembly connected thereto, a sucker rod and a polish rod operating through said valve assembly, said valve assembly having a central discharge chamber and a valve movably mounted on said polish rod, packing for said valve including a sleeve formed on the valve and provided with a chamber therein, and a beveled seat in said chamber, packing in said chamber resting in said seat, a beveled washer mounted on said packing, a spring mounted on said packing, and a perforated plug screwed into said sleeve and bearing against said spring.

In testimony whereof, I set my hand, this 3d day of February, 1930.

FRED DOWNEY.
